UNITED STATES PATENT OFFICE.

WILLIAM H. EISENHART, OF YORK, PENNSYLVANIA, ASSIGNOR TO JOHN C. SCHMIDT, OF SAME PLACE.

LINK FOR CHAINS.

SPECIFICATION forming part of Letters Patent No. 544,759, dated August 20, 1895.

Application filed May 25, 1895. Serial No. 550,711. (No model.)

To all whom it may concern:

Be it known that I, WILLIAM H. EISENHART, of York, in the county of York and State of Pennsylvania, have invented certain new and useful Improvements in Links for Chains; and I do hereby declare the following to be a full, clear, and exact description of the same, reference being had to the accompanying drawings, forming a part of this specification, and to the letters of reference marked thereon.

This invention has for its object to provide a link for chains which shall be simple, strong, and capable of being manufactured by automatic machinery, when so desired.

The invention consists in certain novel details of construction and combinations and arrangements of parts, all as will be now described, and pointed out particularly in the appended claims.

Referring to the accompanying drawings, Figure 1 is a perspective view of a link made in accordance with my invention. Figs. 2 and 3 are similar views of slightly-modified forms.

Like letters of reference in the several figures indicate the same parts.

In carrying out my invention each link is formed by a single rod or bar of metal, which, starting from a central point is extended in both directions, the ends reflexed, and one end formed into an eye or loop which embraces the opposite end and central portion of the bar or rod.

Referring specifically now to Fig. 1, it will be seen that the bar A has its ends bent back or reflexed, forming the loop ends B B of the link, one end being formed into an eye or loop C, embracing the opposite end and central portion of the bar. In this preferred construction, Fig. 1, the ends of the bar are bent back on opposite sides or in opposite directions and the central portion of the bar is bent diagonally of the link, forming in effect a figure 8. The end D of the bar extends beyond the loop, and is again reflexed and passed through the loop in the form of a hook. With the parts

in this position, the eye is tightened and the whole constitutes a most efficient chain-link. It is not essential, however, that the end D should extend outside of the eye, but it may extend directly through the eye, as shown in Fig. 2, where the hook end D turns out instead of in. Instead of forming a hook D for the end passing through the eye, the said end may be headed up, as shown in Fig. 3, where a head or crooked portion E is formed on the extreme end for preventing the said end from drawing back through the loop when strain is brought to bear on the link.

The simplicity in forming a link of this character at once commends it to a manufacturer, as the rod or bar may have one end doubled back and the other end brought back and given a turn around the central portion and opposite end, forming the eye complete.

The manufacture may be carried out by hand or by automatic machinery, such as would at once occur to those skilled in the art of chain manufacture.

Having thus described my invention, what I claim as new is—

1. A chain link formed of a rod or bar of metal having the ends reflexed and one end formed into an eye or loop embracing the central portion and opposite end of the bar; substantially as described.

2. A chain link formed of a rod or bar of metal having the ends reflexed in opposite directions, and one end formed into an eye or loop embracing the central portion and opposite end of the bar; substantially as described.

3. A chain link formed of a rod or bar of metal having the ends reflexed, one end formed into a hook and the opposite end formed into an eye embracing the hook and central portion of the bar; substantially as described.

WILLIAM H. EISENHART.
